ROOF CONSTRUCTION

Filed May 31, 1929

UNITED STATES PATENT OFFICE

HERBERT W. REEL, OF HINSDALE, ILLINOIS, ASSIGNOR TO UNITED STATES GYPSUM COMPANY, OF CHICAGO, ILLINOIS, A CORPORATION OF ILLINOIS

ROOF CONSTRUCTION

Application filed May 31, 1929. Serial No. 367,171.

This invention relates to building constructions and has reference more particularly to precast tile construction adapted to be used for roofs or floors.

In the construction of sloping roofs at an angle to the horizontal precast tiles made of gypsum or other suitable material, are generally supported at the ends of the tile upon steel purlins. The space between the tile is usually filled with a grout such as a mixture of gypsum stucco and water. It is desirable that the tile be securely anchored to the purlins so that tornadoes or other disturbing causes will not lift the tiles from the purlins. It is also desirable to have the space between the ends of the tiles so arranged that the grout will readily flow in under the action of gravity to completely fill said space. It is also desirable that the precast tiles be provided with reinforcing members which present a maximum bearing surface for the ends of the tile.

An object of this invention, therefore, is to provide a precast tile for use on roofs which will be firmly anchored to the purlins.

Another object of the invention is to provide a precast tile the ends of which are beveled to provide a space between the ends of the abutting tiles which will readily permit grout to flow in and fill said space under the action of gravity.

A further object of the invention is to provide a precast tile for roof and floor construction which has reinforcing members providing a maximum bearing surface adjacent the abutting ends of adjoining tiles; also to improve building constructions in other respects hereinafter specified and claimed.

Reference is to be had to the accompanying drawings forming a part of this specification, in which

Figure 1 is a sectional, perspective view of a portion of a roof employing my improved precast tiles,

Figure 2 is a perspective view of one of the tile of the present invention,

Figure 3 is a fragmentary sectional view through a pair of the improved tiles in position,

Figure 4 is a fragmentary elevation of one end of the tile,

Figure 5 is a fragmentary plan view of a modified form of tile used for floor construction, and

Figure 6 is a sectional elevation of the tile shown in Figure 5 as applied to a floor.

The supporting members for a roof usually consist of inclined beams 10, often in the form of steel channels, and smaller channels 11 are supported transversely on and secured to the beams 10, said channels 11 spanning the distance between a pair of adjoining beams 10. In my preferred construction, the upper flanges 12 of the channels 11 are usually directed upwardly along the incline so that the tile can be readily attached thereto, but said flanges may be turned downwardly if desired.

My improved tile 15 is preferably precast from a material such as gypsum and consists of a flat rectangular slab of the material having embedded reinforcement 16 of any desired construction, such as an electrically welded wire mat having longitudinal and cross wires. The ends of the tile 15 are provided with beveled edges 17, the two abutting ends 17 of a given tile being substantially parallel. Each end of my tile is also preferably provided with a transversely extending groove 18 along the under surface of each end, said grooves being adapted to receive the upper flanges 12 of the purlins. The purlins 11 are spaced apart a sufficient distance so that a space 19 is left between the ends of adjoining tiles and grouting grooves 20 are moulded into the upper corners of the tile. Grout 21, usually formed of a mixture of gypsum stucco and water, is then poured into the spaces 19 and groove 20, the beveled edges 17 serving to cause the space 19 to be inclined upwardly and thus be at a favorable angle to permit the grout to flow downwardly under the action of gravity until it strikes the upper flanges 12 of the purlins, or is stopped somewhat above said flanges by suitable shoulders formed on the tiles.

One of the salient features of my invention consists in providing clips 23 having an inclined section 24 and a horizontal section 25

embedded in one end of the tile 15. The clip 23 also has a reversely bent attaching flange 26 adapted to partially enclose the upper flange 12 of the purlin and thus firmly attach 5 the tile to the purlins. There are preferably two clips 23 on one end of each tile, and the other end of a given tile interlocking with the clipped end of the adjoining tile by means of the beveled surface 17. Thus the beveled 10 surface 17 not only provides a favorable inclination for pouring the grout but also serves to interlock one tile with another with a minimum number of clips and so as to prevent the tile from being lifted from the purlins 11 by tornadoes or other extraneous forces. In the lower end of each tile, a slot 15 28 is provided which straddles the clip 23 of the adjoining tile and permits maximum bearing surface of the ends of the tile upon 20 the flange 12 of the purlins.

When the tiles are to be used for floors, the outstanding ends of the clips 23 are split to form one section 26a which is bent rearwardly to partially enclose the upper flange 25 12a of the purlin 11 while the other section or flange 30 of said clip extends outwardly in the same plane with the clip 23 and serves to form an additional bearing support for the 30 end of the adjoining tile 15a. A suitable groove or notch 31 is provided in the bottom of the adjacent tile in order to receive this outstanding flange 30 of the clip. With this construction, the tile may be used on floors and sufficient bearing surface for the ends of 35 the tiles is provided even when the upper flange 12a of the purlin is very narrow and when the purlins 11a are irregularly spaced.

While the foregoing description represents 40 a practical embodiment of my invention, I do not wish to limit myself precisely to these details, since manifestly, the same may be considerably varied without departing from the spirit of the invention as defined in the appended claims.

45 Having thus described my invention, I claim as new and desire to secure by Letters Patent:

1. In a roof construction, a plurality of 50 metallic purlins arranged at an angle to the horizontal, outstanding flanges on said purlins, precast slabs supported by said purlins, clips of a length less than the length of such slab and embedded in the upper ends of said slabs said clip being adapted to engage the 55 flange of a purlin so as to secure said slab to said purlin, beveled edges formed upon the lower end of the adjacent tile adapted to interlock with a similar beveled edge upon the upper edge of the adjoining tile to form an interlocking connection to prevent the displacement of said tiles from said purlins.

2. In a roof construction, a plurality of 60 substantially parallel support members, precast tile supported by said support members 65 and spanning the distance therebetween, clips

embedded in said tiles and having sections extending from said tiles, said sections being adapted to provide bearing surface for a part of the adjoining tile, said sections also having portions adapted to engage with said supporting members to prevent displacement 70 of said tiles from the latter.

3. In a roof construction, a plurality of metallic purlins arranged at an angle to the horizontal, outstanding flanges on said purlins, precast slabs supported by said purlins with each end of each slab resting directly on a purlin, a clip of a length less than the length of said slab and embedded in the upper end of each slab, said clip being adapted 75 to engage the flange of a purlin so as to secure said slab to said purlin, said roof construction having grouting grooves formed by the ends of the slabs and extending upwardly at an angle to the horizontal from a point intermediate the edges of said flange, and a reinforcing mat embedded in said slab independently of said clips.

HERBERT W. REEL.
